UNITED STATES PATENT OFFICE.

JAMES P. OLSEN, JR., OF SALT LAKE CITY, UTAH.

AIRSHIP.

1,031,461.

Specification of Letters Patent.

Patented July 2, 1912.

Application filed February 26, 1912. Serial No. 679,952.

To all whom it may concern:

Be it known that I, JAMES P. OLSEN, Jr., a citizen of the United States, residing at Salt Lake City, in the county of Salt Lake 5 and State of Utah, have invented certain new and useful Improvements in Airships, of which the following is a specification.

My invention relates to improvements in airships and refers particularly to mechanisms for propelling and maintaining the lateral balance or equilibrium of the lifting planes or wings.

The leading object of the invention is to provide an airship having simple, efficient 15 and practical mechanism for propelling the airship upon the principle of a flying bird.

Another object of the invention is to provide a novel form of lifting wings which will create and pocket its own air upon a 20 down stroke and will allow the air to pass directly through the wings on an up stroke, thereby obtaining a maximum degree of efficiency for elevating purposes with a minimum expenditure of energy for over- 25 coming the air pressure or resistance, and thus overcoming the dangerous so called "holes in the air" often encountered by aviators in their flights.

A further object of the invention is to 30 provide an airship which will carry a novel and simple form of emergency plane or canopy to be used upon the occurrence of an accident.

Other objects of the invention are to provide 35 an airship which will have a simple and efficient steering mechanism, said mechanism being adjustable both laterally and vertically to control both the upward and downward direction of the machine and the right and left motion; which will be of 40 extremely light weight but of great durability and simplicity of construction; and which will be at all times under perfect control of the operator.

To attain the desired objects, my invention 45 broadly stated, resides in the provision of an airship having a main frame carrying a driving engine and a plurality of adjustably mounted wings driven therefrom; an 50 emergency plane disposed above the main frame, and an auxiliary frame arranged rearwardly of the main frame and carrying the steering mechanism, and the invention

more specifically stated consisting in the provision of an airship embodying novel 55 features of construction and combination of parts for service, substantially as disclosed herein.

In order that the detailed construction and operation of the invention may be 60 clearly understood and its may advantages be fully appreciated, I have illustrated in the accompanying drawings an airship constructed in accordance with and embodying the principles of the invention, it being un- 65 derstood that I do not limit myself to the precise details of construction shown therein, but reserve the right to make such changes and modifications as come within the spirit and scope of the invention. 70

Figure 1 is a side elevation of the complete machine, the engine being shown in dotted lines. Fig. 2 is a perspective view of the main frame and driving mechanism of the airship, showing the detailed construction and operation of the propelling mechanism. Fig. 3 is a perspective view of the steering mechanism of the airship. Fig. 4 is a top plan view on a reduced scale of the airship showing the shape of the emergency 80 plane or parachute. Fig. 5 is a perspective view of one of the wings detached. Fig. 6 is a perspective view on an enlarged scale of a portion of one of the wings and the means for limiting the tilting of the wing. 85 Fig. 7 is a sectional view of a fragment of one of the wings showing the method of attachment to the frame, and Fig. 8 is a detail view, in elevation, of the clutch mechanism for throwing the engine shaft into and 90 out of operative position. Figs. 9, 10, 11, 12, 13 and 14 represent detail views of parts of my mechanism.

In the accompanying drawings, in which I have employed similar numerals of reference to denote corresponding parts in the several views: the numeral 1 designates the main frame, of any desired material and shape, but preferably composed of a plurality of light bars joined together to 100 form a rectangular-shaped open supporting framework.

Journalized upon the lower longitudinal frame bars 2 of the main frame are the supporting trucks 3 carrying the ground wheels 105 3', the purpose of which is obvious. Mount-

ed upon the upper longitudinal frame bars 4 of the main frame and disposed thereabove at a suitable angle of incidence by means of the uprights 5, is the emergency 5 plane or canopy 6, which consists of a tapering frame having its central longitudinal portion terminating at each end in a triangular-shaped plane 6^a and 6^b, the apex of the forward plane being slightly concaved as at 6^c to offer the least possible resistance to the air. Diverging rearwardly from the center of the plane are the diagonal planes 6^d and 6^e. The entire plane is covered with any desired material 7 and 10 acts as a canopy or parachute in case of an accident, the rear ends of the plane being connected to the lower frame bars 2 by means of the inclined braces 7', while the 15 peculiar shape of the canopy permits the machine to fly through the air with the minimum resistance.

Connecting the upper and lower frame bars 4 and 2 are the series of uprights 8, while the upper frame bars are connected 25 to each other by the transverse bars 9, and the lower frame bars are similarly connected by the transverse bars 10, the whole forming a rectangular-shaped supporting frame.

Suitably supported upon the frame 1 and 30 indicated in dotted lines, Fig. 1, is the driving engine 10', the shaft 11 of which carries the gear 12 upon its outer end, meshing with a gear 13, mounted upon the shaft 14, journaled upon the intermediate transverse 35 bars 10 of the lower frame bars. To throw the gears 12 and 13 into and out of operative position, I provide an operating lever 15 and a segmental rack 16, secured upon the frame bars 2, a dog 17 being connected 40 to the grip 18 of the lever and engaging the teeth of the rack 16, while the shaft 11 and lever 15 are connected by means of a rod 19, the lever being arranged within easy access of the operator's seat 20, likewise carried by the frame bars 2. The shaft 14 is provided near each end with the pairs of 45 cranks 21, slidably mounted upon which are the lower inclined slotted ends of the levers 22, of triangular shape, to the upper 50 ends of which are pivoted the pairs of front wings 23 and the rear wings 24, respectively. These wings, as will be seen by reference to Figs. 5 and 6, are composed of a surrounding rim or frame 25, to which is 55 pivoted a plurality of downwardly inclined slats 26. Passing under each wing are three wires 26', one disposed centrally thereof and the other two along each edge of the wings, the purpose of which is to accommodate 60 date the slats to the upward and downward movement of the wings. Thus when the wings are being raised, the slats will open automatically and allow the passage of the air therethrough, offering but little surface 65 to the action of the air and thus reducing

the resistance to a minimum. When the wings are being lowered however, the slats are closed and fit over each other, thus pocketing the air under the wings and preventing the formation of the so called 70 "holes in the air," which result in accident to the aviator frequently.

Passing centrally over the slats 26 and suitably secured to the frame 25 is the rod 27, the inner end of which is incased in a 75 sleeve 28, mounted in a bracket 28' upon the frame bars 4, said sleeve having a pair of depending ears 29 to which is pivotally connected the upper end of the lever 22, while to relieve the rod 27 of any undue strain, a 80 cable 30 is fastened at one end to each wing frame and has its other end connected to the lower portion of the lever.

To provide a tilting movement for the wings, a bracket 31 is secured to one side of 85 each of the wings and is provided with an outwardly extending pin or lug 32 over which passes the outer end 33 of the bracket 34, the inner end of which is looped at 35 to fit over the frame bar 4, and this construction affords a simple and efficient construction whereby a tilting movement is imparted to the wings.

By reference to Fig. 1 it will be seen that the upper and lower frame bars 4 and 2, 95 respectively, of the main frame are extended rearwardly and gradually converge, terminating in the rectangular frame 36, in which is located my improved steering mechanism. Pivoted approximately intermediate the 100 vertical length of the uprights 36' of the frame 36 is the horizontal pintle 37, carrying the horizontal rudder 38 which controls the upward and downward direction of the flight. Also pivoted to the uprights of the 10 frame 36 is the pair of oppositely disposed vertical guide rods 39, over and around whose ends and the extremities of the horizontal rudder pass the controlling wires 40, the forward ends of which gradually converge as they approach the forward end of 11 the machine.

The apparatus for controlling the lateral movement of the machine consists of a vertical rudder 41, having a central cut out 11 portion to form the pair of outwardly diverging arms 42 and 43, the inner ends of which are pivoted to the vertical pintle 44, revolvably mounted in the sockets 45 of the upper and lower horizontal members 46 of 12 the frame 36, while each arm is provided with a horizontally disposed guide rod 47 and 48, over and around the ends of which pass the controlling wires 49 and 50 for each 13 of the arms. By inspection of Fig. 1, it will be seen that all of the controlling wires meet at a common point and are guided toward the front end of the airship through the guide eyes 50', depending from the frame 14 bars 2. The wires for controlling the ver-

tical movement of the machine are fastened to each end of the vertical guide rods 51, pivoted to the transverse shaft 52 of the steering wheel, which shaft is pivoted at 53 to the frame bars 2 at its outer extremities and supports intermediate its length the inclined steering wheel 54. The wires for controlling the lateral flight of the airship pass over a drum 55 carried by each of the lower frame bars 2 and are directed upwardly to and over the sheave 56 of the wheel.

From this construction, the operation of the steering mechanism will be apparent and briefly stated is as follows:—The vertical flight of the machine is controlled by means of the horizontal rudder 38, pivoted to the frame 36, the controlling wires being passed over the tips of the rudder and forwardly along the frame bars 2 at each side to the guide rod 51, which is connected with the horizontal shaft 52. Inasmuch as the steering wheel is pivoted upon this shaft, a forward tilt of the wheel will give an upward motion to the rudder, whereas a backward tilt of the wheel will give a downward motion, as will be readily understood. The lateral flight of the airship is controlled by means of the vertical rudder 41, the controlling wires passing over the drums 55 located on each side of the frame bars 2 and thence upward and over the sheave 56, the movement of the wheel governing the direction of the lateral flight.

The operation of the lifting wings is, as before stated, on the same principle as the flight of a bird, and briefly stated is as follows: The shaft 14 receives rotary motion from the engine and transmits this motion to the levers 22 through the medium of the pairs of cranks. As the levers have their lower ends slotted to slide upon the cranks, the rotary motion is thus transformed into reciprocating motion and is imparted to the wings upon the upper ends of the levers, which are in this manner made to work up and down upon their pivots. These wings work in pairs and in the drawings the rear right hand wing and forward left hand wing are shown as working in unison and are in raised position, while the remaining pair are in lowered position, which arrangement affords an equal pull at all times and insures a perfect maintenance of equilibrium.

While I have shown and described but two pairs of wings, it will be understood that I do not limit myself to this number, but that any number of pairs may be used, dependent upon the size and capacity of the airship, the underlying principle of the invention residing in the arrangement of the wings in oppositely operating pairs to evenly distribute the pull.

From the foregoing description, taken in

connection with the drawings, it will be apparent to all that I have accomplished the objects set forth above, and that the airship will be safe, extremely simple in construction, and practical and efficient from every point of view.

In Figs. 9 and 10 are shown on an enlarged scale a modified and preferred construction of the means connected to the wings to more clearly illustrate this part of my mechanism.

In Figs. 11, 12, 13 and 14, are shown on an enlarged scale detail views of the connection between the rocker arms, frame, and wings, for the purpose of more clearly illustrating the novel construction of this mechanism of my invention. In this construction, the rocker arms have secured thereto at their upper ends, the sleeves 28 to which are secured the yokes 60, formed with bearings 80 or journals 61, which fit in the bearing boxes carried by the frame and consisting of the lower member 62 and the detachable upper members or caps 63.

I claim:—

1. In an airship, a main frame, wings reciprocally mounted thereon, and means including curved arms slidable on the main frame and connected to said wings for tilting the wings.

2. In an airship, a main frame, wings reciprocally mounted thereon, means including curved arms slidable on the main frame and connected to said wings for tilting the wings, and means for permitting the passage of air through said wings upon the upward stroke of the wings.

3. In an airship, a main frame, wings reciprocally mounted thereon, said wings consisting of a plurality of slats hinged to the wing frame, means passing along the underfaces of the wings for permitting the automatic opening and closing of the slats, a bracket secured to each wing, and arms slidably mounted upon the main frame and connected to said brackets for tilting the wings.

4. In an airship, the combination with a main frame, of wings reciprocally mounted thereon, and provided with automatic opening and closing devices hinged thereto, a bracket secured to each wing, and arms slidably mounted upon the main frame and connected to said brackets for tilting the wings.

5. In an airship, the combination with a main frame, of wings mounted thereon, a rod extending medially over each wing, automatic opening and closing devices hinged to the wing frame, a sleeve incasing the inner end of each wing rod and provided with depending ears, and levers of substantially right-angled configuration connected to said ears at their upper ends for reciprocating the wings.

6. In an airship, the combination with a main frame, of wings mounted thereon, a rod extending medially over each wing, slats hinged to the wings, a plurality of controlling cords passing under each wing to control the automatic opening and closing of the slats, a sleeve incasing the inner end of each wing rod and provided with depending ears, a bracket secured to each wing, 10 arms slideable upon the main frame and connected to said brackets for tilting the wings, and means connected to said ears for reciprocating the wings.

7. In an airship, the combination with a main frame, of wings mounted thereon, a rod extending medially over each wing, slats hinged to the wings, a plurality of controlling cords passing under each wing to control the automatic opening and closing of the slats, a sleeve incasing the inner end of each wing rod and provided with depending ears, a bracket secured to the wing frame and provided with an outwardly projected lug, an arm secured to the main frame and 20 working over said lug, and means for reciprocating the wings.

8. In an airship, the combination of the supporting frame, a driving shaft mounted therein, and formed with two pairs of double cranks, two pairs of levers connected with said cranks, wings connected to the levers, means including arms slideable on the frame and connected to the wings for reciprocating said wings, an engine mounted in the frame and connected to the driving shaft, and mechanism for throwing the engine into and out of connection with the driving shaft.

9. In an airship, the combination of the main frame, the tapering canopy supported above the main frame, the auxiliary frame, the rudders mounted in said frame and capable of movement vertically and laterally, means for manually operating the rudders, 40 a driving mechanism mounted in the frame, wings mounted upon the frame and connected with the driving mechanism, brackets formed upon said wings, and arms slideable upon the frame engaging the brackets to 45 provide a tilting movement for the wings.

10. In an airship, the combination of the main frame, the tapering canopy supported above the main frame, the auxiliary frame, the rudders mounted in said frame and capable of a vertical and a lateral movement, 55 means for manually operating the rudders, and a driving mechanism mounted in the frame, said driving mechanism consisting of a driving shaft having two sets of double cranks, an engine for driving the shaft, levers having slots in their lower ends fitting upon the double cranks, wings pivoted upon the frame and connected to the upper ends of said levers.

65 11. In an airship, in combination with a

main frame, a tapering secondary frame mounted thereabove and having a concaved apex and a pair of rearwardly diverging planes, a driving engine mounted on the main frame, a cranked shaft driven thereby, 70 right angled shaped levers having their lower ends slotted to engage the cranks of said shaft and having wings provided with automatic opening and closing devices pivotally mounted upon their upper ends, arms mounted upon the main frame and connected to said wings, and steering mechanism for controlling the vertical and lateral flight of the airship.

12. In an airship, in combination with a main frame, a secondary frame mounted thereabove, a driving engine mounted on the main frame, right-angled shaped levers operatively connected with the driving engine and provided with wings at their upper ends, arms slideable upon the main frame and connected to said wings for tilting same, an open rectangular frame disposed rearwardly of the main frame, a horizontal rudder and a vertical rudder pivoted to said frame, and a steering wheel located near the forward end of the main frame and connected with the horizontal and vertical rudders for controlling the vertical and lateral flight of the airship.

13. In an airship, a frame, a driving shaft carried thereby, wings carried by the frame, and connections between the wings and driving shaft comprising triangular-shaped levers slotted at their bases to engage the shaft and carrying sleeves at their apices, yokes secured to said sleeves and formed with journals, and bearing boxes carried by the frame fitting said journals of the sleeves.

14. In an airship, a frame, driving means carried thereby, a shaft carried by the frame centrally of its longitudinal length and connected to the driving means, oppositely arranged pairs of wings mounted on the frame, connections between the shaft and wings for operating the wings, and curved arms connected to the frame and slideable thereon for tilting the wings.

15. In an airship, a frame, a driving shaft carried thereby, wings carried by the frame, and right triangular levers having slotted bases engaging the shaft and pivoted to the wings at their apices for operating said wings.

16. In an airship, a frame, a driving shaft carried thereby, wings carried by the frame, sleeves on the wings, and right triangular levers having slotted bases engaging the shaft and pivoted to the sleeves on the wings at their apices for operating said wings.

17. In an airship, a frame, a driving shaft carried thereby, wings carried by the frame, right triangular levers having slotted bases engaging the shaft and pivoted to the wings

at their apices for operating said wings, and means for tilting said wings in a horizontal plane.

18. In an airship, a main frame, a driving shaft carried thereby, wings carried by the frame, a second frame, a steering mechanism therein, a steering device mounted on the main frame, and connected with the steering mechanism of the second frame, and levers having their bases slotted to engage over the driving shaft and pivoted to the wings at their apices for operating said wings.

19. In an airship, a main frame, a driving shaft carried thereby, wings carried by the frame, a second frame, a steering mechanism therein, a steering device mounted on the main frame and connected with the steering mechanism of the second frame, an auxiliary frame mounted upon the main frame, levers having their bases slotted to engage over the driving shaft and pivoted to the wings at their apices for operating said

wings, and means slidable upon the main frame and engaging the wings for tilting 25 same in a horizontal plane.

20. In an airship, a main frame, a cranked driving shaft carried centrally thereby, wings mounted upon the main frame upon each side thereof, a second frame, a steering mechanism therein, a steering device on the main frame and connected with the steering mechanism of the second frame, an auxiliary frame mounted above the main frame, and connections including right triangular 30 35 levers having slotted bases to engage the cranks of the driving shaft and pivotally connected to the wings at their apices for operating the wings.

In testimony whereof I affix my signature 40 in presence of two witnesses.
